METHOD OF MAKING COUPLINGS

Malcolm E. Mitchell, Peter E. Mortensen, and
Harold W. Fowler, Oakland, Calif.; said
Mitchell assignor to said Mortensen and said
Fowler

Original application April 16, 1934, Serial No.
720,760, now Patent No. 2,044,252, dated June
16, 1936. Divided and this application Febru-
ary 2, 1935, Serial No. 4,712

2 Claims. (Cl. 29—157)

The invention relates to coupling members such as used to readily attach and detach sections or extensions of fluid circuits as air pressure systems and more particularly to the means 5 and method of construction of one of the coupling members. The present case is a divisional application of our copending application Serial Number 720,760, filed April 16, 1934 issued as Patent No. 2,044,252 on June 16, 1936 and the sub-
10 ject matter herein claimed is taken from the aforesaid application.

In our previous patent application Serial Number 720,760 we have disclosed and claimed a coupling of the character described which is constructed in a manner concealing the means of detachment of the coupling sections whereby the surreptitious removal of any portion of the air line is made substantially impossible without detection thereof by the attendant in charge of 15 the apparatus. The coupling utilizes a section having a certain inside construction necessary to perfect this operation and it is an object of the present invention to provide a means and method for making this construction possible.

20 The invention possesses other objects and features of advantage, some of which, with the foregoing, will be set forth in the following description of the preferred form of the invention which is illustrated in the drawing accompanying and 25 forming part of the specification. It is to be understood, however, that variations in the showing made by the said drawing and description may be adopted within the scope of the invention as set forth in the claims.

30 Referring to said drawing:

Figure 1 is a longitudinal sectional view of a coupling constructed in accordance with our invention with the separate sections thereof attached.

40 Figure 2 is a transverse sectional view of the coupling and is taken on the plane of line 2—2 of Figure 1.

Figure 3 is a side elevation shown partly in 45 section of a tool constructed in accordance with the present invention and shown operatively associated with a tool and coupling section supporting means.

Figure 4 is a transverse sectional view of the 50 tool and is taken substantially on the plane of the line 4—4 of Figure 3.

Figure 5 is a view similar to Figure 3 but showing the engagement of the tool in the coupling section.

55 Figure 6 is an elevational view of a reamer

adapted to complete the forming operation of the coupling section.

With reference to the drawing, the coupling 11 of our invention comprises detachable male and female sections 12 and 13 which are arranged for telescopic engagement at their ends 14 and 16 and are preferably threaded at their opposite ends 17 and 18 to facilitate the connection of the sections to a fluid line. Extending longitudinally through the sections are aligned 10 bores 19 and 21 for conveying fluid through the coupling. Means for sealing the sections against leakage when coupled, here comprises a packing washer 22 which is mounted in the bore 21 and arranged to engage about the end 14 of the male member, the latter being preferably formed with a slight taper to afford a wedged engagement with the washer. The washer further serves with the members detached as a seat for a valve 23 which is mounted for axial movement 20 in the bore 21 and is normally urged by a spring 24 to seat against the washer in passage closing position and is displaceable from such position only by and upon insertion of the male end 14 through the washer. As here shown the female 25 section is comprised of two parts including a main body casing 25 and a hollow end plug 26 therefor which defines the aforesaid engageable outer end 18 of the section and which extends centrally into the casing 25 for clamping the 30 washer 22 in position against a retaining ring 27. Preferably formed integrally with the member 26 and extending into the passage 21 in spaced relation to the washer 22 is an annular shoulder 29 which defines with the latter a 35 chamber for the valve 23 and affords in addition a support for the outer end of the valve spring 24.

Thus with the members detached the valve 40 will be urged both by the fluid flow and by the spring 24 into passage closing position against the packing washer to prevent leakage from the fluid from the female section. On the other hand upon attachment of the sections, the end 14 of the male member will engage and displace 45 the valve to place the bores of the sections in communication, while at the same time the end 14 will be seated in the washer to prevent leakage from the male section.

Heretofore the connection between the male 50 and female sections usually included a transverse pin or the like carried by the male section and which engaged in a bayonet slot in the female section so that on drawing the sections together and then twisting one relative to the other a 55

fastening of the sections was effected. In this type of connection the pin was of circular section and as a result could be forcefully twisted from a seated position in the slot. Also the pin as a rule extended through the bore in the male section and in this way not only obstructed fluid flow but was a ready source of leakage should the pin become loosely held as a result of handling or rough usage. In accordance with the coupling of our invention, however, means of connection between the coupling member is so arranged as to entirely avoid possible disconnection of the sections or leakage in the manner aforesaid. In addition and as a particularly important and novel feature of the invention, the attachment means is arranged to completely conceal the manner of disassembly of the coupling so as to render the latter's disconnection by other than the method provided for practically impossible. This latter feature is carried out in the present invention by arranging the bayonet slot portion 31 of the connection entirely within the bore 21 at the end 16 of the female section and forming opposed slot engaging lugs or projections 32 on the interfitting end 14 of the male section, whereby with the sections attached both the slots and projections will be entirely concealed within the section 13. As here shown, the portion 31 consists of two diametrically opposed slots which extend from the open end of the bore 21 inwardly to an annular chamber 33. Thus upon insertion of the projections into the slots and effecting first a relative axial movement of the sections until the projections are moved to the chamber 33 and then effecting a relative rotary twist of the sections, the projections will be moved into locked engagement behind the outer shoulder 37 of the chamber. Retention of the projections in this latter position is here arranged to be effected by forming in the shoulder at diametrically opposed points intermediate the slots 31, a pair of sockets 38 arranged to receive and interlock with the projections. Since the insertion of the male section is resisted jointly by the spring 24 and the fluid flow and as a result the resisting force will be applied in drawing the projections against the shoulder when the same are engaged as aforesaid, the movement of the projections into the sockets when aligned and a resultant locking of the parts will be insured. As an important feature of our invention and serving to prevent twisting of the projections from the sockets, the latter are both formed of rectangular section so that no incline is available on the interengaged sides thereof for permitting a longitudinal disengaging movement incident to a forceful twisting of the projections and sockets. Thus with the members attached it is first necessary to move the sections toward each other to disengage the sockets and lugs and then rotate the sections to position the lugs opposite the slots 31 for ready withdrawal. When the coupling is attached as shown in Figures 1 and 2, the sections are so closely associated with each other as to disguise this initial longitudinal movement and as will be clear no other manipulation of the coupling sections such as twisting or pulling will be productive of their disassociation.

In previous couplings with which we are familiar it has been the practice of providing bayonet guide portions such as the grooves 31 here shown by cutting longitudinal slots through the female section which slots extend completely through and to the outside of the section side walls, and to provide the offset for locking portions of the

slot by simply cutting sidewise from the inner end of the slot or by drilling the section at a portion contiguous with the inner ends of the slots. Since the operations entailed in forming these previous constructions are well known and commonly used in machine shop practice, the manufacture of the female section of the coupling presented no particular difficulty. In the present coupling however, wherein the guide portions 31 and the sockets 38 are formed entirely within the bore 21 of the casing 25 and are completely inaccessible for forming by the usual apparatus found in machine shops, the manufacture of the female section of the coupling requires the use of both a special apparatus and a new process of formation. In the case of the female section 25 as here disclosed, the same may be initially prepared prior to the formation of the grooves and sockets 31 and 38 by first drilling axially through the member from the outer end 50 thereof with a drill diameter slightly larger than the male end 14, then reaming from the same end to define the shoulder 37 and a seat 51 and then tapping the reamed bore adjacent the end 18 to form internal threads for the hollow plug member 26. Our new process of forming the aforesaid grooves and sockets consists briefly in punching from the reduced bore portion of the section between the shoulder 37 and the end 16 the grooves 31 while supporting the inner wall of the bore, and then depressing the sockets 38 while supporting both the side walls of the bore and the walls of the grooves 31. Preferably following the punching operation, the end 16 of the section is counterdrilled, and reamed, as indicated in Figure 6 in order to remove any bur or swelling incurred by the punching.

The punching of the grooves and sockets as well as the supporting of the bore side walls and grooves during the punching operation is arranged to be effected by a special tool 53. With reference to Figures 3, 4 and 5 the tool comprises a cylindrical body portion 56 which is arranged to slidably engage in the bore of the female section and support the side walls thereof during the punching operation and is provided on opposite sides thereof with a pair of offset rectangular projections 54 which are arranged on the forceful movement of the tool through the bore to engage the shoulder 37 and shear from the reduced bore portion the grooves 31. Provided also on the periphery of the body portion 53 of the tool and at substantially right angles to the projections 54 is a second pair of offset rectangular projections 55 which serve to engage the shoulder 37 and depress the sockets 38 therein after the grooves 31 have been sheared from the side walls of the bore. To effect forming of the sockets only after the formation of the grooves has been completed or substantially so, the projections 55 are spaced longitudinally from the projections 54 so that their operation will be retarded from that of the projections 54. It is important during the pressing of the recesses 38 and the tremendous strain to which the metal of the coupling is thereby subjected, that the side walls of the grooves 31 be held against partial closing or other distortion. For this purpose the projections 54 are extended longitudinally along the body portion of the tool a distance substantially equal to the length of the grooves 31 so that after the forming of these grooves the projections 54 will lie snugly therein and hold the side walls thereof against any possible distortion due to stress on the metal incurred by the pressing out of the

5   sockets 38. After the pressing operation the bore of the section at the grooves 31 is preferably rounded and the end 16 flared by means of a reamer 59 as indicated in Figure 6, to remove any bur or distortion caused by the punching out 5 of the grooves and sockets.

10   As indicated in Figures 3 and 5 an end 61 of the tool may be mounted in an ordinary punch press 62 and the coupling section 25 positioned 10 on the work support 63 thereof within a guard 64 for holding the section against withdrawal with the tool.

15   We claim:

15   1. In a method of forming a tubular coupling section having a portion of the bore thereof reduced adjacent an end thereof to define a shoulder spaced from said end, and forming a longitudinal guide groove in the wall of said bore from said shoulder to said end which comprises the 20 following steps, supporting the wall of said reduced bore portion against distortion and forcing a tool longitudinally through said bore while so supported for punching out said groove, by

a portion of said tool and subsequently forming a locking recess in said shoulder by another portion of said tool.

2. In a method of forming a coupling section provided with a bore therethrough and having a portion of said bore reduced adjacent an end thereof to define a shoulder in said bore spaced from said end, and forming longitudinal guide grooves in the wall of said bore from said shoulder to said end and of forming locking recesses 10 in said shoulder which comprises the following steps, supporting the wall of said reduced bore portion against distortion and forcing a tool longitudinally through said bore while so supported for punching out said grooves, and then while 15 supporting said bore wall as aforesaid supporting said grooves against distortion and forcefully engaging a tool with said shoulder to depress longitudinally therein said recesses.
